UNITED STATES PATENT OFFICE.

CHARLES FAYER, OF NEW YORK, N. Y., ASSIGNOR TO WAPPLER ELECTRIC CO., INC., A CORPORATION OF NEW YORK.

HIGH-TENSION RECTIFIER.

1,320,040.

Specification of Letters Patent.

Patented Oct. 28, 1919.

Application filed May 28, 1918. Serial No. 237,161.

To all whom it may concern:

Be it known that I, CHARLES FAYER, a citizen of the United States, residing in the city of New York, borough of Bronx, in the county and State of New York, have invented 5 certain new and useful Improvements in High-Tension Rectifiers, of which the following is a full, clear, and exact description.

My invention relates to current rectifiers

10 of a kind suitable for use in connection with high tension currents and admitting of general use, and especially adapted for service in connection with currents adapted for X-ray work.

15 More particularly stated, I seek to produce a rectifier in which I avoid the use of revolving commutators and thus get rid of the inherent defects thereof, and in which the opening and closing of the high tension 20 circuits is accomplished by reciprocating movements of switch arms, so arranged that the contact mechanism is always visible for purposes of inspection, and that undesirable arcs, coronas, brush discharges and the like 25 are avoided with comparative ease.

I also seek to give the various parts of the 30 rectifier such form and arrangement that the contact members are as far as practicable each entirely isolated, in order that the insulation may be maintained as nearly perfect as possible between the stationary contact members and the contact members movable 35 relatively to the stationary contact members, except at the precise instant of contact. Furthermore, I seek to give a comparatively 40 lengthy stroke to each of the movable contact members in order that, other factors being equal, its speed may be increased and the abruptness of breaking contact thus increased.

Further than this, I seek to improve the insulation of the various movable parts as well as the stationary parts, by completely 45 submerging practically all parts, including the synchronous motor and the rectifying switch, in a tank of insulating liquid, preferably oil.

In addition, I provide an improved filter 50 and means for causing the oil to circulate within the tank and pass through the filter, in such manner as to gather up and deposit in the filter all impurities present in the oil, including flakes of carbon formed inciden-

tal to the action of the rectifying switch in breaking contact within the oil.

Reference is made to the accompanying drawing forming a part of this specification, in which like letters indicate like parts throughout the several views.

Figure 1 is a view, partly in section and partly in side elevation, of my high tension rectifier complete.

Fig. 2 is a section on the line 2—2 of Fig. 1, looking in the direction indicated by the arrows, and showing the structure of the filter and parts immediately associated therewith.

Fig. 3 is a section on the line 3—3 of Fig. 1, looking in the direction indicated by the arrows, and showing the rectifying switch.

Fig. 4 is a fragmentary perspective of one of the commutator arms of the rectifying switch.

Fig. 5 is a diagram of the wiring.

I will first describe the wiring and parts 75 immediately associated therewith, including the rectifying switch and its connections.

A pair of alternating current mains are shown at 1, 2, a high potential transformer at 3, and a vertically disposed board at 4, 80 serving to support most of the working parts. The board is mounted upon spacing posts 4^a carried by a synchronous motor 5. This motor bears the legend Synchronous 85 motor. Connected to it are a pair of wires 6, 7, which are also connected to a hand switch 8, provided with a handle 9. Two wires 10, 11 extend from the switch 8 to the mains 2, 1.

Two wires 12, 13 extend from the mains 90 1, 2 to a hand switch 14, and connected to the latter are two wires 16, 15.

The wire 16 is connected to a variable resistance rheostat 17, and a wire 18 extends from this rheostat to the primary winding 95 19 of the high potential transformer 3. The wire 15 connects this winding 19 with the hand switch 14.

The transformer 3 is provided with a number of secondary windings 20, 21, 22, 23, 100 which are connected in series with each other by wires 24, 25. Connected with these secondary windings are wires 26, 27, 28, 29. The wire 26 leads to a junction 30, and from this junction a wire 31 leads to a contact 105 button 32. A wire 33 leads from the junc-

tion 30 to a contact button 34. The wire 27 leads to a junction 27^a, and from the latter a wire 27^b leads to a contact button 35. A wire 36 leads from the junction 27^a to a contact button 37.

The wire 28 leads to a junction 38, and from this junction a wire 29 leads to a contact button 40. A wire 41 leads from the junction 38 to a contact button 42. The wire 29 is connected with a junction 29^a, and from the latter a wire 29^b extends to a contact button 43. From the junction 29^a a wire 44 leads to a contact button 45.

The arrangement of the contact buttons 40, 45, 42 and 43 is similar to that of the contact buttons 32, 37, 34 and 35 above described.

The board 4 is provided with four rocker heads 45, 46, 47 and 48, each mounted upon a bolt 45^a, serving as a binding post. Mounted upon these rocker heads are four switch arms 49, 50, 51 and 52. The several switch arms are alike. That is, each has the form shown at 49 in Fig. 4, and consists of three wires disposed in the same plane and parallel to each other, these wires extending through the adjacent rocking comb 54. The switch arm moves back and forth, as indicated by arrows at the bottom of Fig. 4.

Crossing the switch arms are two sliding bars 53 of insulating material, and pivotally mounted upon these bars, so as to rock relatively thereto, are four rocking combs 54. The form of one of these rocking combs may be understood from Fig. 4. To accommodate each rocking comb, the rocking bar is slightly cut away to form a facet 56. The outer or free ends of the sliding bars are of slightly reduced diameter, and extend through stationary bearings 57.

Connected with the pivot pins 45 and 48 are wires 58, 59, which lead to the terminals of an X-ray tube, or some equivalent device, not shown. The polarity of current in the wires 48, 49 is unitary, and is here indicated by plus and minus signs.

A milliampere meter is shown at 61, and may be placed in any convenient location. A wire 62 extends from the milliampere meter to the pivot pin 46, as indicated more particularly in Fig. 5. A wire 63 is connected with the binding post of the pivot pin 47, and with a wire 64 leading to the ground at 65. By a junction 60, a wire 66 is connected with the wires 63 and 64, and leads to the millampere meter 61.

The synchronous motor 5 is provided with a revolute armature shaft 67. Secured firmly upon this shaft and revolute therewith is a disk 68, carrying a pin 69. This pin extends into a slot 70 in a plate 71, this plate being mounted between a pair of bearing plates 72, the latter being grooved slightly to form a slideway in which the plate 71 can slide back and forth freely in

the direction of its length, the shaft 47 and disk 68 being turned in the direction indicated by the arrow in Fig. 3.

The parts are so arranged that as the armature shaft 67 rotates the sliding plate 70 moves back and forth, as aforesaid. The movements of the sliding plate 70 cause the sliding bars 53 to reciprocate endwise, and in so doing they cause the switch arms 49, 50, 51, 52 to rock back and forth, and thus at short but definite intervals of time, corresponding to definite phasal conditions of alternating current in the mains 1, 2, to open and close various circuits, hereinafter traced.

The parts are so connected, proportioned and arranged that, when the device is in action, each time the switch arms rest momentarily upon any set or group of the contact buttons with which they are capable of engagement, a circuit is completed through all of the switch arms. In any circuit thus completed the current always flows in the same direction through the switch arms, and consequently all discharges through the terminal wires 58, 59 are in one direction. Moreover, the parts are so proportioned and arranged that at the exact instant any circuit is thus completed through the switch arms and contact buttons, the potential wave is at or near its maximum. It follows as a consequence that whenever the switch arms are moved off of the contact members, the break in the circuit is very abrupt, as it necessarily takes place at an instant while the potential is near the peak of the waves.

Thus the switch arms 49, 50, 51 and 52, by making and breaking contact with the contact buttons at predetermined intervals of time corresponding to phasal conditions or stages of the line current, serve to rectify the secondary currents. Further, the switch arms, by the duration of their contact with the buttons, virtually suppress all portions of the current in which the potential drops below a desired minimum. In other words, the switch arms pick out the high potential peaks of the waves, and prevent the flow of currents at all other periods of the cycle.

The synchronous motor 5 is mounted upon a pedestal 73, which rests upon the bottom of a tank 75, containing a volume of oil 76. A transformer 3, with its wiring as shown diagrammatically in Fig. 5 or in the usual or any desired manner, is located within the oil tank, as shown in Fig. 1. The tank is provided with a cover 77.

Located within the tank 75 and mounted upon the pedestal 73 is a hollow casting 78, provided with a discharge orifice 79 having the form of a round hole. The casting 78 is further provided with a pair of guides 79, extending vertically and together composing a slideway. Removably mounted within this slideway is a filter frame 80, provided with a handle 81 whereby it may

be removed. The handle 81 extends upwardly through a slot 82, with which the cover 77 is provided. The filter frame carries a back plate 83, provided with perforations 84, and easily removable. The filter frame also carries an asbestos board 85, which is also removable and serves as a septum or filtering member. The operator, by grasping the handle 81 and removing 5 the filter frame and parts carried thereby, can next remove the back plate 83 and the asbestos board 85 from the filter frame, and can replace these parts or substitute new ones, as desired. This arrangement enables the 10 operator to frequently renew the asbestos board, as the filter is used continuously or from time to time, as desired.

The shaft 67 carries a disk 86, provided with radially disposed slots 87, the plane 20 of each slot being oblique to the plane of the disk. This disk slot occupies the orifice 79, and serves as an impeller for forcing the oil continuously through the orifice, as indicated by arrows in Fig. 1. This causes 25 the oil to be continuously drawn in through the filter, and thus to be cleansed continuously. It also causes the oil to circulate freely within the tank.

It is absolutely necessary to keep the oil 30 free from contamination, in order that the insulation may be as nearly perfect as possible, and to prevent the formation of arcs whenever the circuit is opened, at or near the peak of the wave by action of the contact mechanism of the rectifying switch. Thus the work of the filter has a direct relation to the thoroughness of the insulation afforded by the oil.

It is a fact that a high tension rectifying 40 switch, having make and break contact mechanism operated in oil, causes flakes of carbon to form in the oil. This probably takes place incidental to the breaking of the circuits. The carbon flakes thus formed, 45 unless taken care of, become diffused throughout the oil, and of course impair the insulating qualities thereof. In my device, however, these carbon flakes are carried along by the circulating oil and deposited in the filter. This not only insures 50 good insulation, but renders uniform the action of the rectifying switch.

It has been found advisable to submerge 55 all working parts, including the motor, within the oil in order to insure complete insulation and to prevent the working parts from producing noise.

The motor and the casting 78 are braced 60 relatively to each other by stay bolts 88, as shown in Fig. 1.

The operation of the filter and parts immediately associated therewith may be readily understood from the foregoing description.

65 I will now describe the action of the recti-

fying mechanism in which high tension currents of unitary direction are to be delivered from the terminal wires 58, 59.

The hand switch 8 is first closed. This energizes the synchronous motor 5 and starts 70 it into action, so that the rotation of the armature shaft actuates the plate 71, the sliding bars 53 and the switch arms 49, 50, 51, 52, as above described.

Each time the sliding bars 53 reach the 75 limit of their travel in one direction, say to the left according to the figure, the arms 49, 50, 51, 52 are brought into engagement with the contact buttons 32, 37, 40, 45, as shown. Each time the bars 53 reach the 80 limit of their travel in the opposite direction, say to the right according to the figure, the switch arms are brought into engagement with the contact buttons 34, 35, 42, 43. During each successive instant midway between the moments when the bar 53 reaches the respective limits of its travel, the switch arms engage the contact buttons 37, 34, 45, 42—the switch arms traveling first in one direction and then in the other. 90

The engagement between the switch arms and contact buttons always takes place at a moment when the potential of the secondary current wave is at or near a peak.

There is one reversal in the direction of 95 the current, as induced in the secondary windings, after each disengagement of the switch arms from the contact buttons. This result is accomplished by so winding the synchronous motor that the current through 100 it is reversed four times for each revolution of the armature shaft. This armature shaft may be readily given a speed of 1800 revolutions per minute, and with this done the apparatus can be used with ordinary 105 commercial currents of 3600 cycles per minute, that is 60 per second, or any other common frequency.

I will now trace the several circuits.

When the hand switch 8 is closed, a circuit is completed through the synchronous motor, as follows: Main 1, wire 11, right member of hand switch 8, wire 7, synchronous motor 5, wire 6, left hand member of switch 8, wire 10, main 2 to power house 110 or other source of current supply (not shown) and thence back to main 1.

The hand switch 14 being closed, a circuit through the primary winding of the transformer is completed as follows: main 120 1, wire 12, right hand member of switch 14, wire 16, rheostat 17, wire 18, primary winding 19, wire 15, left hand member of switch 14, wire 13, main 2 to source of current supply, thence to main 1. 125

With the sliding bars 53 at the limits of their travel to the left, as shown, the circuit of the wave of high tension current induced in the secondary windings 20, 21, 22, and 23, is as follows: winding 20, wires 26 and 130

- 31, contact button 32, switch arm 49, wire 58, X-ray tube or the like, not shown, wire 59, switch arm 52, contact button 45, wires 44 and 29, winding 23, wire 25, winding 22, 5 wires 28 and 29, contact button 40, switch arm 51, wires 63 and 66 (grounded through wire 64), milliamperes meter 61, wire 62, switch arm 50, contact button 37, wires 36 and 27, winding 21, wire 24, back to winding 20.
- 10 The high tension current, flowing through the circuit just traced, has a unitary direction indicated, say, by the plus and minus signs shown at the top of Fig. 5.

As the armature shaft 67 turns, in the direction indicated in Fig. 3 by the arrow, when the pin 69 passes directly over the armature shaft, the switch arms 49, 50, 51 and 52 momentarily make sliding engagement with the contact buttons 37, 34, 45, 20 42, and at the same instant a high tension current wave of reversed polarity induced 25 in the secondary windings 20, 21, 22, 23 is near or at its peak and flows through the switch arms in the same direction as before. The circuit may be traced as follows: winding 20, wire 24, winding 21, wire 27, wire 36, contact button 37, switch arm 49 (now engaging the same), wire 58, X-ray tube not shown, wire 59, switch arm 52, contact button 42 (now engaged thereby), wire 41, wire 28, winding 22, wire 25, winding 23, wire 29, wire 44, contact button 45, switch arm 51, wires 63 and 66, milliamperes meter 61, wire 62, switch 30 50, contact button 34, wire 33 and wire 26 back to winding 20.

The rotation of the armature shaft 67 being continued still further, the pin 69 reaches its extreme position to the right, and as a result the plate 71 and the bars 53 are 40 carried to the limit of travel to the right, so that the switch arms now momentarily engage the contact buttons 34, 35, 42 and 43. This contact takes place at or near the moment when the reversed wave of high potential current is at or near its peak.

The new circuit is traced as follows: winding 20, wires 26 and 33, contact button 34, switch arm 49, wire 58, X-ray tube, not shown, wire 59, switch arm 52, contact button 43, wire 29^b, junction 29^a, wire 29, winding 23, wire 25, winding 22, wire 28, wire 41, contact button 42, switch arm 51, wires 63 and 66, milliamperes meter 61, wire 62, switch arm 50, contact button 35, wires 27^b, 55 27, winding 21, and wire 24 back to winding 20.

Further rotation of the armature shaft brings the pin 69 to the lowermost point of the circle in which it moves, and causes the 60 plate 71 and sliding rod 53 to assume such position that the switch arms again engage the contact buttons 37, 34, 45, 42. This contact takes place at or near the moment when the reversed wave of high potential

current is at or near its peak. The circuit 65 thus completed is identical in all respects with the one above traced relative to the engagement of the switch arms with the contact buttons 37, 34, 45, 42.

As the rotation of the motor shaft continues a little further, all movable parts are brought back into their initial positions, and the cycle of operations is thus completed.

It will be noted that as the orbit of the pin 69 is circular and the motion conferred by it upon the sliding bars 53 is rectilinear, the speed of travel of these sliding bars is variable, the bars moving at low speed when near the proximate limits of their travel, and moving at higher speeds at other points 80 of their travel. Thus the switch arms travel at varying rates of speed. In order, however, that the duration of contact between the switch arms and contact buttons may be substantially uniform for the different contact buttons, I place the various contact buttons in such positions, relatively to each other and to the centers of oscillation of the switch arms, that when the speed of a switch arm is slowed down as the switch arm reaches the proximate limit of its travel, the distance in which the arm can travel while engaging a contact button is shortened. In other words, reduction in speed of the arm is compensated by reduction in the length of the path of travel while in contact. This result is accomplished by so arranging the parts that each switch arm, at the limit of its travel in either direction, can not move over a large portion of the 95 button before beginning its return stroke. It moves up on the button a little distance, and then recedes.

The currents generated and rectified as above described have comparatively little 105 amperage, as they are essentially made up of the peaks of approximately maximum potential, of the secondary currents generated by the transformer.

I do not limit myself to the precise mechanism shown and described in detail, as variations may be made therefrom without departing from the spirit of my invention.

The scope of my invention is commensurate with my claims, which are as follows:—

1. The combination of a receptacle containing a body of liquid insulating material, a synchronous motor located within said receptacle and submerged in said liquid insulating material, a filter for said liquid insulating material, mechanism driven by said synchronous motor for forcing said liquid insulating material through said filter, a transformer mounted within said receptacle and submerged in said liquid insulating material, a source of alternating current common to said motor and said transformer, for energizing the same, and a 115 120 125

rectifying switch provided with make and break contact mechanism and submerged in said liquid insulating material.

2. The combination of an oil tank holding a body of free oil, a synchronous motor located within said tank and submerged in said oil, said motor having a revoluble shaft, a filter located within said tank, an impeller carried by said revoluble shaft for forcing 10 said oil continuously through said filter, a rectifying switch located within said tank and submerged in said body of oil, connections from said shaft to said rectifying switch for enabling said shaft to drive said switch, and a source of alternating current 15 common to said synchronous motor and rectifying switch.

3. The combination of a receptacle, a body 20 of liquid insulating material contained within said receptacle, a rectifying switch provided with make and break contact mechanism, said rectifying switch being mounted within said receptacle and submerged within said body of insulating material so that incidental to the action of said 25 rectifying switch the liquid insulating material is contaminated by impurities, and filter mechanism associated with said receptacle for removing said impurities from 30 said liquid insulating material.

4. In a device of the character described the combination of a synchronous motor, a transformer provided with a primary winding and a secondary winding, means for 35 supplying alternating current to said synchronous motor and said secondary winding, a plurality of pivotally mounted switch arms, connections therefrom to said synchronous motor for enabling said synchronous motor 40 to actuate said switch arms, and contact buttons connected with said secondary windings and periodically engaged and disengaged by said switch arms for the purpose of rectifying the currents from said secondary winding.

5. In a device of the character described the combination of a synchronous motor, a transformer provided with a primary winding and a secondary winding, means for 50 supplying alternating current to said synchronous motor and to said primary winding, a sliding bar connected with said synchronous motor and receiving therefrom a rectilinear motion, switch arms of conducting material connected with said sliding bar and receiving therefrom a rectilinear motion, and contact buttons connected with

said secondary winding and so disposed relatively to the path of travel of said switch arms that the alternating currents 60 from said secondary winding are rectified as they flow from said contact buttons through said switch arms.

6. In a device of the character described the combination of a synchronous motor, a 65 transformer provided with a primary winding and a secondary winding, means for supplying alternating current to said synchronous motor and said secondary winding, a plurality of contact buttons connected with 70 said secondary winding, reciprocating members connected with said synchronous motor and moved in synchronism therewith, said reciprocating members being arranged to engage and disengage said contact buttons 75 in order to rectify the currents generated in said secondary winding, said contact buttons being so distributed relatively to the paths of travel of said reciprocating members as to equalize the duration of contact between the reciprocating contact members and the contact buttons.

7. In a device of the character described, the combination of a synchronous motor, a transformer provided with a primary winding and a secondary winding, means for 85 supplying alternating current to said synchronous motor and said secondary winding, a longitudinal member connected with said synchronous motor and arranged to receive 90 therefrom a thrust motion in the general direction of the length of said longitudinal member, and mechanism connected with said reciprocating member and actuated thereby for rectifying the currents induced in said 95 secondary winding.

8. In a device of the character described, the combination of a synchronous motor, a transformer provided with a primary winding and a secondary winding, means for 100 supplying alternating current to said synchronous motor and said primary winding, a longitudinal bar connected with said synchronous motor and movable back and forth in the general direction of the length of 105 said bar, rectifying switch mechanism connected with said bar and actuated by movements thereof for rectifying the currents generated in said secondary winding, and means for maintaining said synchronous 110 motor, said transformer, said bar and said rectifying switch mechanism submerged in a liquid insulating material.

CHARLES FAYER.
